DISPLAY CONSTRUCTION

Barfield Fredrick Grantham, P.O. Box 1320, Deland, Fla.

Filed Sept. 6, 1955, Ser. No. 532,586

3 Claims. (Cl. 211—177)

This invention relates to exterior exhibition and interior showroom display equipment.

At the present time, many products are displayed at sales shows through the use of especially constructed booths. Many of these sales shows take place in exhibit halls which vary in capacity and shape, and the space allotted for individual display purposes varies accordingly.

In the past, it has been necessary to re-construct new booths or display assemblies to comply with the different space requirements, since a single display booth is often unsuited for use in different exhibit halls. This is a costly procedure. In addition, these display booths generally are bulky, costly to transport and easily damaged during shipment, and extremely expensive to store between periods of use.

Accordingly, an object of the present invention is to provide a new and improved display structure which may be easily adapted for use in any exhibit hall.

Another object of the present invention is to provide a basic display box and a variety of novel connection forming means whereby a plurality of these display boxes may be interconnected to form a variety of self-supporting display structures of any appropriate size.

Another object of the present invention is to provide a display box and connection forming means, as described above, having uniform inter-related constructions whereby a plurality of boxes and connection forming means may be interchanged for accommodating ease and quickness of assembly of a display construction without the use of special tools.

Yet another object of the present invention is to provide new and improved display bracket for use with the display boxes.

Still another object of the present invention is to provide a novel connection for inter-connecting the display boxes of the invention.

These and other objects and advantages of the present invention will be apparent from the following description of one form of the invention, taken with the accompanying drawings, wherein:

Fig. 1 illustrates a display construction formed by the use of the display boxes and connection forming means of the present invention;

Fig. 2 is a perspective view illustrating a display box adapted for use as a display table;

Fig. 3 is a perspective view illustrating a display box in use as an upstanding display frame;

Fig. 4 is a perspective view of a display box including a plurality of brackets adapted to support the products to be displayed;

Fig. 5 is an enlarged front sectional view illustrating one use of the connection forming means of the invention;

Figs. 6 through 12, illustrate a number of the connecting forming means of the invention;

Fig. 13 is an enlarged view in front elevation of a plug or part of the connection forming means; and

2

Fig. 14 is an enlarged view in vertical section illustrating one of the connection forming means of the invention.

The basic display box or unit 20 of the invention comprises a substantially square frame or tray having side members 21 and a top member 22 and a bottom member 23. The display box is also provided with a flat back wall 24, as illustrated in Fig. 4. The sides and the top and bottom members or flanges of the box are provided with a plurality of equally spaced apart openings 25 which may be used for interconnecting the display boxes or for supporting a plurality of the display brackets, as subsequently more fully described.

The display boxes 20 may be interconnected by the use of a variety of connector blocks, as illustrated in Figs. 6 through 12. These blocks are referred to herein-after as: a T-shaped block 26 (Fig. 9), an L-shaped block 27 (Fig. 10), a double-end block or connector 28 (Fig. 11), and a single-end spacing block 29 (Fig. 12). These blocks are provided with spaced apart openings 30 which are adapted to register with the openings 25 in the side, top and bottom members of each of the display boxes 20.

The openings 30 and the openings 25 in the display boxes are adapted to receive a cylindrical, resilient connector member 31, as illustrated in Fig. 13. This connector member, for the purposes of illustration, is shown as a cylindrical hollow piece of rubber tubing, it being understood that the connector member may be formed of a solid, resilient material and need not necessarily be cylindrical in form.

More particularly, the openings 25 in the display boxes are provided with substantially the same diameter 32. The openings 30 in the blocks are also provided with substantially the same diameter 33, but this diameter is slightly less than the diameter 32 of the openings 25 in the display boxes. Further, the outer normal diameter 34 of the resilient connector 31 is slightly greater than the diameter 32 of the openings in the display boxes.

Thus, when the connector 31 is inserted through an opening 30 in a block and then through an opening 25 in a display box, the walls of the openings 30 and 25 compress and grip the connector 31 and firmly retain it in a wedged position, as illustrated in Fig. 14, whereby the block 29 and box 20 are substantially firmly interconnected. Fig. 14 illustrates the compressed condition of the several sections of a connector 31 when it has been wedged through the opening 30 in a block and the lower end of the connector has been wedged into an opening 25 in a display box.

Fig. 5 illustrates the use of a single-end block 29 disposed in a substantially vertical position between the two adjacent side members 21 of two display boxes 20. These boxes are interconnected by a connector 31 which extends through the aligned openings 25 in the upper portions of the side members of the boxes and through the opening 30 in the single-end block 29. A similar connection may be made between the lower portions of the side members. The flat surface of the blocks 29 bear against the outer surfaces of the side members, and aid in giving the connections a substantial degree of rigidity. Thus, it may be seen that by use of the resilient connectors and the variety of blocks, a plurality of display boxes 20 may be easily and quickly interconnected to form a large variety of display structures. Also, due to the diameters of the openings in the display boxes and the blocks, the connectors are more tightly wedged into position in the block openings 30 than they are in the openings 25 of the display boxes. Thus an assembly of boxes may be easily and quickly dis-assembled by merely separating each display box from its respective

connectors 31, each connector 31 remaining wedged in its block rather than sliding free from the block and remaining in the display box as the display box is moved away from the block.

Fig. 5 also illustrates the use of a double-end type block 28 which is arranged on the top members 22 of the adjacent display boxes. The openings 30 of the block 28 are in registry with the respective openings 25 in the top members of the display boxes. The opening 30 in the righthand end portion of the double-end block receives a connector 31, as previously described, and the upper end 35 of this connector is received in an opening 25 in the bottom member 23 of another display box 20. The lower end of this connector is received through the registered opening 25 in the top member of the right hand box. The opening in the left hand portion of the double end block is shown in use with a modified form of the connector. This connector 36 is substantially two-thirds as long as the connector 31, heretofore described, so that the upper end 37 of the connector is disposed in a substantially flush relation with the upper surface of the connector block 28. If desired, this connection may be strengthened by driving a peg 38 into the top of the connector 36 for wedging the walls of the connector tightly between the peg 38 and the wall of the opening 30 in the block. The length of the connectors 31 is slightly less than the combined double width of a box member and one block whereby the ends of the connectors 31 remain hidden from sight. The connections shown in Fig. 5 are merely for purposes of illustration, it being understood that the number and arrangements of the connections may vary according to each particular assembly of boxes and according to the degree of rigidity required by the assembly.

In order to facilitate the assembling of a plurality of display boxes 20 into a display construction, as illustrated in Fig. 1, the display boxes and the connection-forming means are provided with a uniform related construction whereby an assembly can be made easily, without the use of special tools. All of the blocks are provided with substantially the same thickness and the spacing of the openings 30 in the blocks and the openings 25 in the display boxes is such that any block may be used in a position where it is needed without the need for selecting a block having a particular thickness. Thus, in the construction illustrated in Fig. 5, a T-shaped block 26 could be substituted for the double-end block 28, and a double-end block could be substituted for the single-end block 29 without varying the overall relationships of the three display boxes 20 as illustrated. The arrangement is such, that when blocks are used in forming an assembly of display boxes, all of the spaces 39 between the boxes are substantially the same whereby the assembly or display construction provides a pleasing appearance no matter from which position the assembly may be viewed.

Also, if desired, the blocks may be formed of a suitably resilient material to aid in strengthening the rigid characteristics of an assembly of the display boxes. Thus, in the construction, as illustrated in Fig. 5, the end block 28 could be formed of this resilient material, and the center lines of the openings 30 in the block could be spaced slightly closer together than the center lines of the laterally spaced apart connector receiving openings 25 in the boxes whereby the connectors 31 would tension the block 28 and provide a somewhat firmer connection. Moreover, the spacing of the openings 25, 30 and the thickness of the connector blocks is such that when a connection is formed, as illustrated in Figs. 6 to 8 inclusive, the ends of the two display boxes are spaced apart a sufficient distance to accommodate the swinging movement of one box around the end of the other box into any desired position as illustrated by dotted lines in Fig. 8.

From the foregoing description, it is apparent that a

plurality of display boxes and connection-forming means may be used to construct an assembly of boxes of substantially any size or configuration. The assembly, as illustrated in Fig. 1, shows a variety of constructions which may be easily made.

The boxes 20 in the first or right hand column are arranged in substantially the same plane, and are interconnected between their upper and lower members 22 and 23 by connections using both the double end and single end type blocks 28 and 29. Also, all of the back-walls 24 of these boxes are turned toward the viewer and may be provided with any suitable advertising matter.

The second column of display boxes is connected to the right hand column by use of the double-end blocks 28, and is spaced rearwardly from the first column. The back wall 24 of the upper display box in the second column is turned rearwardly to accommodate the insertion of product display brackets and the like in the display box, as subsequently more fully described.

The uppermost display boxes 20 in the fourth and fifth columns are illustrated with the backwall removed and an ornamental bracket 40 inserted within the frame of each box to aid in providing an assembly which is pleasing to the eye. Also, the two display boxes beneath the ornamental boxes have been removed to provide an opening 41 in the assembly, behind which a salesman may stand to pass out advertising literature. The opening 41 might also be used for a recessed backwardly extending assembly, not shown, wherein additional products could be displayed.

In order to provide the assembly with a suitable amount of stability, the left hand end portion of the sixth column of display boxes is connected to the mid portion of seventh column of display boxes by a plurality of T-shaped blocks 26 whereby the seventh column is disposed substantially normal to the plane of the sixth column of display boxes.

The eighth column is provided with another opening 42 between the upper and lower boxes in the column, 40 whereby, due to the versatility of the construction, the upper box in the column extends outwardly from the assembly and is connected only to the upper display box in the seventh column.

Finally, the only display box in the ninth column is connected to the lowermost box in the eighth column by the use of two double-end blocks 28 whereby the box is disposed outwardly at an angle from the display assembly.

Thus, it may be seen that a large variety of constructions may be formed by use of the basic display box and the connection means, the assembly illustrated in Fig. 1 being shown only for illustrating some of the possible connections and configurations which may be made.

As illustrated in Fig. 4, the display boxes may be provided with a plurality of brackets 43 for displaying products. All of the brackets 43 are provided with a through hole 44 adjacent to their rear portions through which a rod 45 is slidably received. The ends of the rod are received in the appropriate openings 25 in the side members 21 of the box 20. The rearmost edge 46 of each bracket 43 is substantially straight and is adapted to bear against the inner-surface of the back wall 24 of the box, whereby the brackets extend outwardly from the open face of the box in a suitably appropriate manner. 60 The outwardly extending portions 47 of the brackets are provided with a variety of shapes for supporting different products.

The versatility of the basic display box 20 is further illustrated in Figs. 2 and 3. As shown in Fig. 2, a display box may be converted into a display table or the like by the use of four legs 48. The upper portions of these legs are provided with through holes 49, which are disposed in registry with the appropriate openings 25 in the box. The oppositely disposed pairs of registered openings and holes receive a pair of the rods 45 whereby the legs

are releasably connected to the box. The holes 49 have substantially the same diameter as the block openings 30 whereby, if desired, the legs 48 may be connected to the box by the resilient connectors 31. The upper edges 50 of the legs are substantially straight and are adapted to bear against the under side of the back wall 24 of the box, whereby the legs are retained in a substantially rigid relation with respect to the box.

As shown in Fig. 3, the display box 20 may also be used as an upstanding individual display assembly by the use of a pair of standards 51. These standards are connected to the outer sides of the side members 21 of the display box and each is provided with a pair of downwardly diverging legs 52. The upper portion of each standard is provided with a pair of vertically spaced apart through holes 53, having substantially the same diameter as the block openings 30 whereby each standard may be connected to the side of the box by a pair of the connectors 31. The standards have substantially the same thickness as the blocks and if desired, the standards 51 may be used in an intermediate position between two adjacent upstanding display boxes 20. In this construction the connectors 31 extend through the openings 25 in the two spaced apart sides of the display boxes and through the holes 53 in the standards. Also, the tops of the display boxes may be connected by the use of a single end block 29 and a double end block 28 as illustrated, and the bottom end of the standards may be further connected by use of a double end block 28 which is disposed between the leg portions of the standard, as shown in Fig. 3.

Thus, it may be seen that there has been provided a new and improved display structure which may be easily adapted for use in substantially any exhibit hall. The basic display boxes of the invention may be quickly and easily assembled into a great variety of different display structures and the display boxes may also be used individually for displaying products as previously described.

The foregoing description has been given for clearness of understanding only, and no unnecessary limitations should be implied therefrom, for it will be apparent to those skilled in the art that variations and changes may be made in the structure of the invention without departing from the spirit and the scope of the appended claims.

What is claimed is:

1. In a display support, the combination which comprises a plurality of juxta-positioned rectangular-shaped trays having back walls with side, bottom and top flanges extended from edges thereof, said side, top and bottom flanges each being of a depth less than one-third of the width of the attached back wall, said flanges having spaced openings therethrough and the openings of the flanges of one tray being in registering relation with the openings of the flanges of an adjoining tray, spacing blocks positioned between the vertical flanges at the sides of the trays, rectangular-shaped connector blocks positioned above and below the top and bottom flanges of the trays, respectively, with openings of the blocks positioned in registering relation with the openings of the top and bottom flanges of the trays, and elongated plugs of resilient material extended through the openings of the blocks and flanges for temporarily retaining the trays in assembled relation whereby products may be displayed thereon.

2. In a display structure, the combination which comprises a plurality of juxta-positioned rectangular-shaped trays assembled to provide a vertically disposed rack, said trays having back walls with side, bottom, and top flanges extended from edges thereof, said side, top and bottom flanges each being of a depth less than one-third of the width of the attached back wall, said flanges having spaced openings therethrough and the openings of the flanges of one tray being in registering relation with the openings of the flanges of adjoining trays, spacing blocks positioned between the flanges at the sides of the trays, connector blocks positioned below and above the bottom and top flanges of the trays with openings of the blocks positioned in registering relation with openings of the flanges, and tubular plugs of resilient material extended through openings of the blocks and flanges for retaining the parts in assembled relation, some of the trays being omitted providing openings through the structure.
3. In a display support, the combination which comprises a plurality of juxta-positioned rectangular-shaped trays having back walls with side, bottom, and top flanges extended from edges thereof, said flanges having spaced openings therethrough and said openings of the flanges of one tray being in registering relation with the openings of the flanges of an adjoining tray, spaced blocks having openings therethrough between the trays and positioned whereby the openings thereof are in registering relation with openings of the trays, and elongated tubular plugs of resilient material extended through the openings of the flanges of the trays and also through openings of the blocks for temporarily retaining the trays in assembled relation, the diameter of the plugs being greater than that of the openings of the flanges whereby the plugs are frictionally retained in said openings, the diameter of the openings of the blocks being less than the diameter of the openings of the flanges whereby the tubular plugs are contracted in the blocks between the flanges.
